DESIGN FOR A JEWELRY RACK

Martin Sacoder, New York, N. Y.

Application May 16, 1945, Serial No. 119,569

Term of patent 3½ years

(Cl. D80—9)

To all whom it may concern:

Be it known that I, Martin Sacoder, a citizen of the United States of America and a resident of the city, county, and State of New York, have invented a new, original, and ornamental Design for a Jewelry Rack, of which the following is a specification, reference being had to the accompanying drawing, forming a part thereof.

On the drawing:

Figure 1 is a view in perspective of a jewelry rack, showing my new design.

Figure 2 is a top plan view of the jewelry rack shown in Figure 1, and

Figure 3 is an end elevational view thereof.

I claim:

The ornamental design for a jewelry rack, as shown.

MARTIN SACODER.
